No. 872,790.

PATENTED DEC. 3, 1907.

E. H. BENNERS.

SIDE FRAME FOR CAR TRUCKS.

APPLICATION FILED JUNE 25, 1907.

UNITED STATES PATENT OFFICE.

EDWIN HENDRY BENNERS, OF ELIZABETH, NEW JERSEY.

SIDE FRAME FOR CAR-TRUCKS.

No. 872,790.

Specification of Letters Patent.

Patented Dec. 3, 1907.

Application filed June 25, 1907. Serial No. 380,673.

To all whom it may concern:

Be it known that I, EDWIN HENDRY BENNERS, a citizen of the United States, residing in Elizabeth, in the county of Union and State of New Jersey, have invented a certain new and useful Side Frame for Car-Trucks, of which the following is a specification.

This invention is a side frame for car trucks, and appertains more particularly to trucks for freight cars.

Great difficulty has been experienced in practice in producing a side frame for trucks which is simple and economical in construction, and yet possess the desired strength and durability.

In the present invention I have accomplished these and other objects, and have designed a frame of the character under consideration possessing a maximum amount of strength with a minimum amount of material. These results have been achieved by constructing certain members of the frame from material having special forms in cross section, and by so distributing the material as to produce the greatest strength at the particular points in the frame which experience has proved are most apt to yield and break when subjected to the heavy loads and strains incident to their use.

The new side frame is simple and economical to construct, can be quickly mounted for use and, in practice, has proven to possess great efficiency and durability.

In the accompanying drawings, I have illustrated one practical embodiment of the invention, but the construction shown therein is to be understood as illustrative only, and not as defining the limits of the invention.

Figure 1 is a plan view of the frame; and Figs. 2 and 3 are side and end views thereof, respectively. Fig. 4 is a sectional view on line 4—4 of Fig. 2. Fig. 5 is a sectional view on line 5—5 of Fig. 2. Fig. 6 is a sectional view on line 6—6 of Fig. 2. Fig. 7 is a sectional view, showing a part of the frame work in elevation, on line 7—7 of Fig. 2. Fig. 8 is a sectional view on line 8—8 of Fig. 2; and Fig. 9 is a sectional view on line 9—9 of Fig. 2.

As will be observed from Fig. 2, the frame is skeletonized and composed of the top member, *a*, preferably arched, the two members *b*, *b'*, extending at an angle therefrom and connected by the base member, *c*,

These parts form a frame, substantially triangular in shape, and extending across which are the uprights, *d*, *d'*, for the purpose of strengthening it.

The member, *a*, in cross section, for the main portion of its length is of the form shown in Fig. 5, the same consisting of the upper web, *e*, having the depending flanges *f*, *f'*, from which extend the reentering flanges, *g*, *g'*.

The members, *b*, *b'*, are substantially rectangular in cross section, as shown in Fig. 9, and are provided at their upper sides with ribs, *h*, *h'*, see Fig. 9.

The base member, *c*, which is skeletonized, is composed of a bottom plate, *i*, side plates, *k*, *k'*, provided at their upper edges, with the laterally extending flanges *k*², *k*³, respectively, end plates, *l*, *l'*, having ribs, *m*, *m'*, *m*², *m*³, extending beyond the side plates, and a web *n*, connecting the side plates. The base member, *c*, is connected with the members *b*, *b'*, by the webs, *o*, *o'*, respectively.

The uprights, *d*, *d'*, are channel shaped in cross section, intermediate their length, as shown in Fig. 8, but above the middle portion of each upright, the side flanges, *p*, *p'*, are widened, as shown in Fig. 6, and are provided with the reentering flanges, *q*, *q'*, see Fig. 6. Each of the uprights, *d*, *d'*, is provided at its upper end, and extending inwardly from the side of the frame, with a hanger, *r*, having a vertical slot, *s*, and a transverse opening, *s'*, adapted to receive a bolt, *t*, whereby the links, *t*', *t*'' are pivotally connected to the hanger for the purpose of suspending the brake beam, as usual. These hangers are cast integral with the uprights, and, by virtue of the additional metal entering into their construction, strengthen the frame at points normally subjected to great strains, and in which respect prior frames were defective.

The top member, *a*, the members, *b*, *b'*, the base member, *c*, the uprights, *d*, *d'*, and the hangers, *r*, are preferably cast in one piece.

The top edge of the base member, *c*, is recessed at *u*, *u'*, see Fig. 2, for the purpose of receiving the angle shaped plates, *v*, *v'*, which serve to connect the two side frames of the truck, tying them together and tending to keep the truck square, the said angle plates being held in place by bolts, *w*, *w'*, and *w*''.

w^3 . The bolts, w' , and w^3 , serve the further function of securing the tie bar, x , to the base member, c , of the frame.

As will be understood the ends of the upper member a , of the frame rest upon and are bolted to the axle boxes, and the tie bar, x , connects the said boxes to the frame and to each other, for the purpose of bracing and retaining them in position.

10. The device as described, possesses pronounced strength and rigidity, being particularly strong at those points which experience has shown to be the most susceptible to breakage, and yet the frame is so shaped, and 15 the metal so distributed, that great strength and durability are secured with a relatively small amount of metal.

Having thus fully described the invention, what I claim as new, and desire to secure by 20 Letters Patent is:

1. In a device of the class described, a top member provided with depending flanges from which extend reentering flanges, two members extending at an angle therefrom, a 25 base member, and uprights connecting the said members.

2. In a device of the class described, a top member, uprights depending therefrom, said uprights being provided with flanges, the 30 said flanges being wider where the uprights join the top member than they are at the points intermediate the length of said uprights.

3. In a device of the class described, a top 35 member, uprights extending therefrom, said uprights being provided with flanges, the said flanges being wider where the uprights join the top member than they are at the points intermediate the length of said uprights and hangers integral with said uprights and below the top member.

4. In a device of the class described, a top member, a skeletonized base member, uprights connecting the top member with the 45 base member, and a re-inforcing member secured to the base member and each of the uprights.

5. In a device of the class described, a top member, inclined members extending therefrom, a skeletonized base member, uprights connecting the top member with the base member, and a re-inforcing member secured to the base member and each of the uprights. 50

6. In a device of the class described, an upper member, a skeletonized base member, and channeled uprights connecting said members. 55

7. In a device of the class described, a skeletonized base member, composed of side 60 and end plates, a web connecting the side plates, the said side plates being provided at their upper edges with laterally extending flanges.

8. In a device of the class described, a skeletonized base member, composed of side 65 and end plates, a bottom plate connecting the side and end plates, a web connecting the side plates, the said side plates being provided at their upper edges with laterally extending flanges. 70

9. In a device of the class described, a top member, a base member, uprights integral with said members, the said base member being provided with two recesses, with a portion of said base member intermediate said 75 recesses, and angle plates seated in the recesses of the base member and separated by said intermediate portion of the said base member, said plates being secured to said base member and the uprights. 80

10. In a device of the class described, a channeled top member, a skeletonized base member, inclined members extending from the top member and provided with ribs, and channeled uprights coöoperating with said 85 upper, inclined, and base members.

In testimony whereof I have signed my name to this specification in the presence of two subscribing witnesses.

EDWIN HENDRY BENNERS.
